UNITED STATES PATENT OFFICE

2,135,105

LATCH

Harry A. Knauff, Pittsburgh, Pa.

Application May 12, 1937, Serial No. 142,145

8 Claims. (Cl. 292—206)

This invention pertains to latching devices, and more particularly, to automatically tightened devices.

In one aspect, my invention deals with improved forms of latching devices which may be used in any suitable association, but which are particularly designed for latching or locking together window sash members.

I have found that latching devices now on the market may be opened by a sneak thief through the agency of a special tool that is inserted between the window sash rails. The tool is worked in a manner to push latch portions back into an unlatched relationship or to move the handle portion to obtain the same result. It seems to be a simple matter for sneak thieves to unlock an ordinary form of window latch.

In view of the above considerations, it has been an object of my invention to provide a new and improved form of latching device;

Another object of my invention has been to provide a form of latching device that will baffle sneak thieves;

Another object of my invention has been to provide an improved form of latching device that may be quickly locked and unlocked by the householder, but that will effectively resist the efforts of a sneak thief to unlock it;

A further object has been to provide a latch device that will automatically tighten when an attempt is made to move it towards an unlocked position when it has been suitably adjusted.

These and many other objects of my invention will appear to those skilled in the art from the following description, the drawing, and the appended claims.

In the drawing:

Figure 1 is a plan section through a window assembly having associated therewith an embodiment of my invention;

Figure 2 is a vertical sectional elevation taken along the lines II—II of Figure 1;

Figure 2A is a vertical sectional detail of the keeper of Figures 1 and 2;

Figure 3 is a vertical section similar to Figure 2, but showing a modified application of my invention;

Figure 4 is a plan view partially in section of a detail of the embodiment of Figure 3;

Figure 5 is a plan view of a modified form of latch keeper;

Figure 6 is a vertical sectional elevation taken along the lines VI—VI of Figure 5;

Figure 7 is a vertical section detail of a preferred form of latch element; and

Figure 8 is a view similar to Figure 7, but showing another preferred form of latch element.

In carrying out my invention, I preferably provide a type of latch keeper lug and latch keeper shoulder that will cooperatively engage adjacent the unlocked position of the device and will maintain such engaged position for the balance of the locking movement of the device. I also preferably provide the keeper lug and latch shoulder portions with wedge-like surfaces that tend to draw the window rails together with a gradually increasing taper or wedge action towards the locking position of the device. However, any suitable form of latch keeper and latch shoulder arrangement may be employed. A feature phase of the present invention lies in the provision of what may be termed auxiliary latching elements that are, in effect, self-latched or automatically tightened when an unauthorized attempt is made to unlock the window.

In the embodiment of my invention shown in Figures 1 and 2, I have represented an outer sash rail 10, a glass window 11 mounted thereon, and an inner sash rail 12. It is customary to mount a latch keeper on the outer sash rail 10 and I have shown a keeper member 13 having an upwardly-extending housing of somewhat semi-circular-like outline that terminates substantially adjacent its center in a latch keeper lug 14. As shown particularly in Figure 2A, the latch keeper lug 14 is preferably wedge-shaped, tapered, or increasingly inclined from the left to the right in Figure 1, or in other words, in the direction of the locking movement.

In Figure 1, I have indicated an unlocked position by the letter A, somewhat central positions by the letters B and C, and a fully locked position by the letter D. I have also provided a bolt or latch housing 16 having upwardly extending side edges of somewhat semi-circular shape that extend horizontally inwardly. As shown, the keeper housing 13 and the bolt housing 16 are mounted in position by suitable screws 15 and are in substantial circular alignment. Adjacent the inner edge of the rail 12 and adjacent its center, the housing 16 is provided with a downwardly-projecting bearing sleeve 17. A latch arm 18 is provided with a bearing pivot 19 that extends downwardly and rotatably within the bearing sleeve 17. A latch element 20 or 20' is securely attached to the lower end of the pivot pin 19 and holds the latch arm 18 in position with respect to the mount sleeve 17. The latch element 20 or 20' is provided with a horizontally-inwardly-extend-

ing portion that terminates in an upwardly-extending latch shoulder. The latch shoulder is preferably provided with an entrant portion adjacent its front or initial latching end; in the embodiment of Figure 7, it preferably increases in inclination or taper upwardly and in thickness from right to left in Figure 1, and thus, from the initial latching to the final latching position. It will thus be seen that the latch element 20 and the keeper lug 14 are increasingly tightly wedged together in a complementary relationship as the latch arm 18 is moved from the position A to the position D. The forward point adjacent the entrant portion of the latch element 20 is adapted to abut a stop shoulder 23 extending inwardly of the housing 16, in order to prevent the latch arm 18 from being moved past the maximum locking position D.

In Figure 8, I have shown a rather abrupt form 20 of shoulder portion of the latch element 20'. The advantage of this type rests particularly upon the fact that its cam edge exerts a full closing or latching force for the greater portion of its length. Thus, play movement of latch arm 18 at a position (for example, between A and B of Figure 1) is positively prevented even when the auxiliary members 16-22 are not adjusted. The shoulder of latch element 20, see Figure 7, gives a more gradual closing movement, and is 30 of advantage when the sash rails are to be brought into alignment by the latching device. However, the auxiliary elements 16-22, when adjusted, prevent leverage on arm 18 about the bearing sleeve 17, even when the latch shoulder element 20 and the latch keeper lug 18 have been moved only partially towards the final position D.

Although I have shown the latch keeper lugs 14 and 14' as mounted substantially centrally 40 of the keeper portions 13 and 13', I also contemplate mounting such lugs somewhat eccentrically in order to increase the wedging action, and, if desirable, to cause the latch shoulder portion 20 to sooner engage therewith.

45 As shown particularly in Figure 1, the outer shell-like edge or face of the latch housing 16 is provided with a cam-like surface that increases in divergence or taper outwardly from the full locked position D to the unlocked position A. The arm 18 is provided with a downwardly depending lug 21 threaded to receive a substantially oblong-shaped thumb nut 22, having a threaded stem portion whose end is adapted to abut against the cam surface. The nut 22 preferably has a somewhat acute angle with respect to the rail 12, in order that sufficient room will be provided to adjust it without cramping the fingers.

It will be seen that the latch arm 18 may be 60 readily moved from the position D to A, or from any intermediate position such as B and C, provided the thumb nut 22 has been screwed outwardly to fully clear the cam surface 16. It will also appear that when the auxiliary element or 65 thumb nut 22 is screwed by the fingers into a relatively tight position against the cam face of the housing 16 in position D, the arm 18 can be moved little if any distance to the right of Figure 1, in view of the increasing divergence of the cam surface and the tendency of the pin end of the element 22 to increasingly dig into such surface.

In view of the above-mentioned auxiliary locking arrangement, the ordinary tool of a sneak thief is useless and only serves to cause the aux-

iliary latching elements to lock the device more tightly. Another advantage of the present invention is that the arm 18 may be moved to an intermediate position, such as B, or C, to effectively hold the sash members locked together. A tool inserted between the sash rails 10 and 12 has difficulty in reaching the arm 18 and if the arm is pulled in either direction, it still maintains the latch keeper lug 14 and the latch shoulder 20 in a locked relation; this is very puzzling to a sneak thief. When the arm 18 is in the position such as C, it is impossible for the sneak thief to get his instrument in position to force the arm past position D and to break the lug 23 and thus to move the latch to an unlocked position in the reverse direction.

Another embodiment of my invention shown in Figures 3 and 4 provides a modified form of housing 16' that is provided with a slightly-inwardly inclined cam face 24 having a continuous circumferential groove for receiving the end of the screw element 22. This arrangement, in effect, strengthens the support of the operating arm 18 and prevents a sneak thief from pushing the arm 18 upwardly about its pivot point 19 and possibly snapping it off. The groove also serves as a wedge guide for the travel of the element 22. The taper of the interlocking portions 14 and 20 or 20', can be much greater than heretofore, due to the supplemental action of the auxiliary 30 means 16-22, and the present form of lock will hold its position regardless of the steepness of the tapered or inclined surfaces.

In Figures 5 and 6, I have shown a stamped or pressed out form of latch keeper 13' having a downwardly-dependant somewhat centrally located latch lug or flange 14'. This distinguishes from the cast form of latch keeper shown in Figures 1, 2, and 2A. It will be apparent to those skilled in the art that the latch keeper 13 or the latch housing 16 may be stamped, pressed, cast, or formed in any other suitable manner. That is, the invention may be equally effective when applied to a cheaper form of stamped metal structure as well as to the more expensive form of cast structure.

Although I have for the purpose of illustration shown several embodiments of my invention, it will be apparent to those skilled in the art that many additions, substitutions, combinations and other suitable arrangements thereof may be employed without departing from the spirit and scope of my invention as indicated in the appended claims.

I claim:

1. In a fastening device having a keeper element, a latch housing element, a latch turnably mounted in said latch housing element and arranged to cooperatively engage said keeper element, and an auxiliary latching device on said latch housing element having means arranged to automatically tighten when said latch is moved toward an unlatching position.
2. In a fastening device having a keeper element adapted to be mounted on a window sash, a latch housing element adapted to be mounted on an adjacent window sash, a latch element pivotally mounted on said latch housing element and arranged to complementarily engage said keeper with an increasing wedging action in one direction of movement thereof, and an auxiliary element associated with said latch element and cooperatively engaging said housing element, said auxiliary element having means arranged to increasingly wedge against said housing element.

when said latch is moved toward an unlocked position.

3. In a fastening device having a keeper element, a latch housing element, a latch member turnably mounted on said housing element and arranged to cooperatively engage said keeper element, said housing element having a cam surface of increasing divergence in one direction thereof, and means cooperatively associated with said latching member and engaging said cam surface for preventing said latch from being unlocked by an unauthorized person.

4. In a fastening device having a keeper element, a housing element, a latch element turnably mounted upon said housing element and adapted to cooperatively engage said keeper element for locking said housing element and said keeper element together, said housing element having a cam surface of increasing thickness in one direction, an auxiliary latch element associated with said first-mentioned latch element and adapted to cooperatively engage said cam surface.

5. In a fastening device having a keeper element, a latch housing element, a latch element turnably arranged with respect to said housing and adapted to cooperatively engage said keeper element for locking said housing and said keeper element together, said latch element being substantially circular in outline and having an abrupt cam surface adjacent one end thereof and a uniform surface for the balance of its length, so that the fastening device will be fully locked for the major portion of movement of said latch element with respect to said housing.

6. In a fastening device having a keeper element, a housing element, a latch element turnably arranged with respect to said housing element and adapted to cooperatively engage said keeper element for locking said housing element and said keeper element together, said housing

element having a grooved cam surface of increasing thickness in one direction, and an auxiliary latch element operably arranged with respect to said first-mentioned latch element and adapted to cooperatively engage said grooved cam surface.

7. In a fastening device adapted to hold a pair of members in a locked association and having a keeper member adapted to be mounted on one of said members and a housing element adapted to be mounted on the other of said members, a bearing on said housing, a latch member pivotally mounted in said bearing and extending outwardly from said latch housing, said latch member having a wedge-shaped latch shoulder portion adapted to cooperatively-engage said keeper member and lock therewith, an operating arm secured to said latch member and extending beyond said housing element, a cam surface of increasing divergence in one direction associated with said housing element, a lug extending from said operating member, a thumb screw mounted in said lug and adapted to cooperatively engage said cam surface for additionally locking said keeper element and said housing element in associated relation.

8. In a fastening device having a stamped metal keeper element having an eccentrically projecting latch portion, a latch housing element, a latch member pivotally mounted on said latch housing and adapted to turn about said housing substantially the distance of half a circle and to cooperatively engage with said latch portion of said keeper element, said housing element having a cam surface increasing in divergence in the direction of movement employed for unlocking the device, and an element extending from said latch element and adapted to cooperatively engage said cam surface for resisting unauthorized attempts to unlock said latch element.

HARRY A. KNAUFF. 40
